UNITED STATES PATENT OFFICE

2,203,511

INDEX SHEET

Arthur A. Tait, Plainfield, N. J.

Application April 6, 1939, Serial No. 266,296

4 Claims. (Cl. 129—16.8)

This invention relates to improvements in index sheets and more particularly to a metal tab index sheet.

The use of a metal index tab upon a flexible index sheet is desirable for indexing loose leaf catalogues for they are indestructible, provide a firm finger grip tab; are easy to read; and are capable of interchangeably receiving different index labels. To directly attach the metal index tab to the flexible index sheet results in the pulling away of the tab and the tearing of the index sheet during ordinary handling.

It is therefore the primary object of the invention to provide a novel means of reinforcing a flexible index sheet to prevent the pulling away of a metal index tab therefrom.

Another feature of the invention resides in a simple and inexpensive means of reinforcing the flexible sheet of a metal tab index sheet so as not to materially increase the cost of manufacture thereof.

Other features of the invention will be apparent as the following specification is read in conjunction with the accompanying drawing, in which:

Figure 1 is a perspective view of one form of my reinforced metal tab index sheet.

Figure 2 is an enlarged transverse sectional view on the line 2—2 of Figure 1.

Figure 3 is a perspective view of a modified form of my invention.

Figure 4 is a fragmentary plan view of a further modified form of the invention.

Figure 5 is an enlarged detail sectional view on the line 5—5 of Figure 4.

Referring to the drawing by reference characters, and at present to the form of the invention shown in Figures 1 and 2, the numeral 10 designates my improved metal tab index sheet in its entirety which includes a rectangular sheet 11 preferably constructed of linen, but it is understood that the same may be of any other flexible material such as paper. One side edge of the sheet 11 is reinforced by linen tape 12 and this reinforced edge constitutes the loose leaf binding edge of the index sheet and is provided with the usual binding holes 13. The opposite side edge is designated by the numeral 14 and constitutes the indexing edge for the sheet 11. Extending across one side of the sheet 11 at any desired location between the top and bottom of the sheet, is a reinforcing strip 15, the same being of a length greater than the width of the sheet 11 to provide an extension portion which is folded over the index edge 14 to a position flat against

the opposite side of the sheet 11. This folded portion of the strip 15 may be termed a reinforcing flap 16 and is of a length to extend only part way across the width of the sheet 11. The reinforcing strip 15 is preferably of kraft 5 gummed stock so as to provide an adhesive bond between the reinforcing strip and the faces of the sheet 11. The adhesive connection is designated 17 in Figure 2 of the drawing. Attached to the reinforced portion of the sheet 11 is a 10 metal index tab 18 which is formed of a single sheet of metal folded upon itself to provide a label receiving head 19, and a pair of spaced attaching tail flanges 20—20. The head 19 is provided with opposed window openings 21—21 15 which are closed by transparent Celluloid strips 22—22 for protecting and displaying the index label 23. The tail flanges 20—20 straddle the folded portion of the strip 15 and embrace the strip 15 and flap 16. Eyelets or other like fastening elements 24 pass through the flanges 20—20, strip 15, flap 16, and sheet 11, so as to rigidly secure the metal index tab 18 to the sheet 11 with the head 19 extending beyond the indexing edge 14 thereof.

From the foregoing description, it will be seen that I have sufficiently reinforced the flexible rupturable sheet 11 at a point where the metal index tab is fixedly secured to the index sheet, thus preventing the accidental pulling away of 20 the metal tab 18 and tearing of the sheet 11.

Indexes of the kind herein shown and described are generally used in connection with loose leaf catalogues and their binders, but it will be understood that the invention may be applied to other types of indexes where reinforcement of the flexible rupturable index sheets are associated with rigid indexing tabs.

In Figure 3 I have illustrated a further modified form wherein a thin sheet steel reinforcing strip 15' is attached to an index sheet 11' by rivets or eyelets 27. The strip 15' is the equivalent to the gummed tape 15 and is folded around the index edge of the sheet in the same manner. The metal index tab 18 is secured to the reinforced portion of the index sheet in the same manner as hereinbefore explained and further explanation is not deemed necessary.

In Figures 4 and 5 I have illustrated a further modification wherein the reinforcing strips 31 are formed from a folded-over strip and are on opposite sides of the index sheet in the same manner as shown in Figures 1 and 2. Folded over the index edge of the sheet 30 and adhesively secured to each side thereof in overlapping rela- 50 55

tion to the strips 31 is a linen shield 32. A small metal index tab 33 is provided and the fastening eyelets 34 pass through both folds of the linen shield 32, strips 31 and sheet 30. This linen shield reinforcement is used with a relatively small metal tab 33 and prevents tearing away of the metal tab which is likely to occur in spite of the kraft paper reinforcing strips.

By extending the reinforcing strips 15, 15', and 31 substantially across the entire width of the index sheets, I prevent the sheets from being accidentally folded when the metal index tabs are pulled upon to effect a turning of the sheet. The resiliency of the thin metal reinforcing strip 15' is such that should the index sheet be bent, the metal strip 15' will serve to return the sheet to a flat condition.

Having thus described the invention, what I claim as new and desire to secure by Letters Patent of the United States is:

1. An index comprising a flexible index sheet, a flexible reinforcing element flatly secured to said sheet and extending substantially entirely thereacross from the indexing edge thereof to provide a reinforced portion extending inwardly from the indexing edge, and a metal index tab secured to the reinforced portion at the indexing edge of said sheet.

2. An index comprising a flexible index sheet of rupturable material, a flexible reinforcing strip

flatly secured to one side of said sheet and extending substantially thereacross from the indexing edge thereof to provide an elongated reinforced portion, a rigid index tab having an attaching portion overlying one end of the reinforcing strip, and fastening elements passing through said attaching portion, reinforcing strip and index sheet.

3. An index comprising a flexible index sheet of tearable material, a flat metal reinforcing element extending substantially across the entire width of one face of said sheet from the indexing edge thereof, fastening means securing said reinforcing element flat against said sheet, and a metal index tab secured to the reinforcing element and said sheet at the indexing edge of the latter.

4. An index comprising a flexible index sheet of tearable material, a relatively thin flat metal reinforcing strip extending substantially across the entire width of one face of said sheet from the index edge thereof, spaced fastening elements passing through the reinforcing strip and index sheet for flatly securing the same together, a metal index tab positioned over the reinforcing strip at the index edge end thereof, and fastening elements passing through the metal index tab, reinforcing strips, and index sheet.

ARTHUR A. TAIT. 30
